DESIGN FOR AN AIRPLANE

Athanas P. Fontaine, San Marino, Calif., assignor
to Vultee Aircraft, Inc., Vultee Field, Calif., a
corporation of Delaware

Application March 15, 1943, Serial No. 109,757

Term of patent 14 years

To all whom it may concern:

Be it known that I, Athanas P. Fontaine, a citizen of the United States, residing at San Marino, in the county of Los Angeles and State of California, have invented a new, original, and ornamental Design for Airplanes, of which the following is a specification, reference being had to the accompanying drawings, forming a part thereof.

In the drawings:

Figure 1 is a plan view of an airplane showing my new design;

Figure 2 is a front elevational view;

Figure 3 is a side elevational view; and

Figure 4 is a perspective view.

I claim:

The ornamental design for an airplane, substantially as shown.

ATHANAS P. FONTAINE.
